UNITED STATES PATENT OFFICE.

ALEXANDER MCPHERSON, OF NEW GLASGOW, NOVA SCOTIA, CANADA.

DOOR-HANGER.

1,156,419.

Specification of Letters Patent.

Patented Oct. 12, 1915.

Application filed November 30, 1914. Serial No. 874,652.

To all whom it may concern:

Be it known that I, ALEXANDER MCPHERSON, a British subject, residing at New Glasgow, in the county of Pictou, in the Province of Nova Scotia, in the Dominion of Canada, have invented new and useful Improvements in Door-Hangers, of which the following is a specification.

My invention relates to hangers to which 10 rolling doors are attached at the top, but is equally applicable for attachment at the bottom, and the objects of my invention are to provide an inexpensive hanger, one not liable to get out of order and having the 15 minimum amount of friction in its operation. I attain these objects by the mechanism illustrated in the accompanying drawing, in which—

Figure 1 is a front view of my invention;—Fig. 2 is a section on line (b c) of Fig. 1.

Similar letters refer to similar parts throughout the several views.

A is the hanger iron to which the door is 25 secured and which contains the door moving mechanism.

B is a channel iron, which is secured to the car or building to which the door is to be connected. The inner faces of the flanges 30 of the channel iron preferably diverge outward and on the inner face of the lower flange is located a substantially half round track iron d. (a) is a grooved metal wheel, the outer side of which may be of slightly 35 greater diameter than the inner side thereof. Said wheel rolls on said track iron (d) and is spaced between said track and the under side of the upper flange of said channel, leaving a slight clearing space at the top, 40 which arrangement not only prevents the wheel from leaving the track, but effectually obviates any possibility of the wheel binding when one end of the door is tilted up, as when the wheel is raised from the track. 45 while it is moving, it will simply roll on the under side of the upper channel flange. (b) is the axle, carrying said wheel and can be formed as an integral part thereof, or rigidly secured to the same by any efficient 50 means. (c. c. c.) are antifriction rollers, carried within the hub of said hanger iron and surrounding said axle on which it revolves, thus insuring the minimum amount of friction, during the operation of moving

the door. (f) is a collar on the outer end 55 of the axle, secured thereto by the pin (e) and by overlapping the rollers (c), which are located parallel with said axle between said wheel and the collar it effectually retains all the moving mechanism in its proper 60 position.

If desirable antifriction balls may be substituted in lieu of rollers without impairing the efficiency of the invention.

Having described and illustrated my invention, what I claim and desire to secure by patent is:

1. In a door hanger, a horizontally disposed channel iron whose flanges extend outward, a strip of substantially semi-circular 70 formation in cross section secured in rigid relation to the upper face of the lowermost flange to form a track, a hanger iron whose upper end is formed to provide a relatively long bearing extending transversely of the 75 hanger iron beyond the front and rear faces of the same, a grooved wheel to roll on said track, an axle for the wheel whose outer end projects beyond the outer end of said bearing, anti-friction rollers disposed between 80 the bearing and the axle, the anti-friction rollers being of substantially the same length as the bearing, a collar detachably secured to the projecting outer end of the axle and engaging the outer end of the bearing to confine said rollers within the bearing and to hold said wheel against lateral displacement with relation to the inner end of the bearing.

2. In a door hanger, a horizontally disposed channel iron whose flanges extend outward and the inner faces of which diverge outward, a strip of substantially semi-circular formation in cross section secured to the upper face of the lowermost flange to 95 form a track, a hanger iron whose upper end is formed to provide a bearing, a grooved wheel to roll on said track, the outer side of the wheel being of slightly greater diameter than the inner side thereof, an axle for 100 the wheel mounted in said bearing, anti-friction rollers disposed between the bearing and the axle, and means to detachably secure the axle in the bearing.

ALEXANDER MCPHERSON.
